INSOLE CEMENTING MACHINE

BACKGROUND OF THE INVENTION

There are many kinds of machines for applying adhesive to insoles but insofar as known none is suitable for applying adhesive exclusively to the end portion of an insole as distinguished from machines which apply adhesive to the overall area to the surface and machines which automatically traverse the entire edge of an insole relative to an applicator roll for applying adhesive to the marginal edge thereof. For this reason it is still common practice to daub the adhesive on the end of an insole with a brush. It is accordingly the purpose of this invention to provide a machine for applying adhesive to one or both ends of an insole and to enable controlling the length to which the adhesive is applied. It is also an object to provide a machine which is substantially automatically operable in that the operator need only to place the insole within the machine and such disposition of the insole in the machine will initiate its operation whereupon the insole will be coated and discharged from the machine. Other objects are to provide a machine which will be easily adjustable for application of adhesive to different lengths, to accommodate insoles of different size, which will be reliable and which will require little or no servicing.

SUMMARY

As herein illustrated, the machine comprises an applicator roll supported for rotation about a horizontal axis, and a gauge stop supported adjacent the upwardly moving side of the applicator roll having a surface normal to a plane tangent to the top of the applicator roll and at a distance therefrom corresponding to the length of the insole to which adhesive is to be applied. There is means for effecting rotation of the applicator roll in a direction such that its surface moves away from the gauge stop and switch means operable when the insole is placed in engagement with the top of the applicator roll and its end pressed against the gauge stop to initiate operation of the machine. A holddown roll is supported above the applicator roll in an elevated position for movement into engagement with the insole resting on the applicator roll and there is means for effecting its movement into engagement with the insole and its rotation substantially simultaneously with the rotation of the applicator roll, and when the tip end of the insole reaches the line of tangency to retract the holddown roll to its elevated position and stop the machine. The applicator roll preferably has two symmetrically disposed adhesive-receiving surfaces located at opposite ends of a given diameter of the roll, each having a leading end and extending peripherally of the roll in a direction opposite to the direction of rotation, and there is means for initially adjusting the roll to position the leading end of one of the surfaces at said line of tangency or optionally to displace it to a predetermined distance with respect thereto.

The drive provided for effecting rotation of the applicator roll rotates it through 180° of rotation each time rotation is initiated.

The invention will now be described in greater detail with reference to the accompanying drawings wherein:

FIG. 1 is a plan view of an insole showing the application of adhesive to the opposite ends of an insole;

FIG. 2 diagrammatically illustrates the relation of the applicator and holddown rolls with an adjustable gauge stop which enables positioning the insole at a predetermined position for application of adhesive to a predetermined length thereof;

FIG. 3 is a diametrical section through an applicator roll showing adhesive-applying surfaces of predetermined peripheral length;

FIG. 4 is a development of the peripheral surface of the applicator roll;

FIG. 5 is an elevation to smaller scale of the machine;

FIG. 6 is an elevation, partly in section, of the upper part of the machine for applying adhesive to an insole according to this invention, showing the applicator roll supported in a receptacle for holding molten adhesive, the holddown roll in an elevated position and the gauge stop;

FIG. 6a is a fragmentary elevation taken on the line 6a-6a of FIG. 6;

FIG. 7 is an elevation taken on the line 7-7 of FIG. 6 showing the applicator roll and the holddown roll above it;

FIG. 8 is a plan view taken on the line 8-8 of FIG. 6, showing the top of the applicator roll and centering means for the end of the sole to hold it centered with respect to the gauge stop and to the applicator roll;

FIG. 8a is a fragmentary elevation taken on the line 8a-8a of FIG. 8;

FIG. 9 is a plan view taken on the line 9-9 of FIG. 5 showing the drive mechanism for the applicator roll and holddown roll;

FIG. 9a is an elevation at the left-hand side of the machine with respect to the front diagrammatically illustrating the chain drive;

FIG. 10 is a detail of the index mechanism for the drive;

FIG. 11 is a view taken on the line 11-11 of FIG. 10; and

FIG. 12 is a layout of the pneumatic control for controlling operation of the machine.

The apparatus disclosed herein is for precoating the area of an insole at the toe and/or heel with an adhesive which may subsequently be activated during a toe-lasting and/or heel-lasting operation to secure the lasting margin along these areas.

FIG. 1 illustrates an insole 10 to which adhesive has been applied both at the toe and heel. The present machine is designed especially to enable applying the adhesive to a selected area, for example, to a substantially U-shaped area 12 at the toe and/or a similar substantially U-shaped area 14 at the heel. It is to be understood, however, that the adhesive may be applied to the entire area at the toe and/or heel rather than to the U-shaped area shown and that it may be extended lengthwise of the insole blank to either decrease the area to which the adhesive is applied or to increase it, and especially to control the width of the band across the end from the tip of the toe toward the heel or from the tip of the heel toward the toe and the length of the band along the sides of the insole from the tip of the toe or the tip of the heel rearwardly or forwardly as the case may be.

The machine is provided with a frame 16 generally rectangular in configuration, supported from the floor by four legs 18. The frame in turn supports in a substantially horizontal plane a table 20 and subjacent thereto vertically spaced shelves 22 and 24. A facing panel covers the front of the frame and obviously the sides and backs of the frame may also be provided with enclosing facing panels if desired.

The operative components of the machine comprise an applicator roll 26 mounted from the shelf 22, as will appear hereinafter, with the surface at the top adjacent an opening in the table 20; a holddown roll 28 also supported from the shelf 22 by means extending upwardly through the opening in the table for movement into engagement with an insole resting on the applicator roll 26 at an appropriate time and for rotation in conjunction therewith to effect movement of the insole in a direction to apply adhesive to the area desired and discharge the insole from the machine when the application of adhesive is completed; and means for effecting rotation of the applicator roll and movement of the holddown roll 28 into and out of operating relation therewith comprising a system of air cylinders and valves shown diagrammatically in FIG. 12 which are, for the most part, mounted on the shelf 24 within the frame.

Diagrammatically as illustrated in FIG. 2 the insole blank 10 is placed between the applicator roll 26 and the holddown roll 28, the latter at this time being elevated from the applicator roll 26, in tangential contact with the upper surface of the applicator roll 26 and with its end abutting an adjustable gauge stop 30 situated at a distance from the top of the applicator roll corresponding to the distance along the insole blank to

which the adhesive is to be applied. Pressure of the end of the sole blank with the gauge stop 30 automatically initiates operation of the machine, as will appear hereinafter, so as simultaneously to bring the holddown roll 28 downwardly into engagement with the insole resting on the applicator roll 26 and effect rotation of the rolls 26 and 28 in opposite directions as indicated by the arrows to retract the insole, that is, back it away from the gauge stop 30 and discharge it so that it slides down an inclined apron 32 mounted in the facing panel into a receptacle situated at the base of the machine for receiving it. Each time an insole is introduced into the machine and initiates operation by engagement with the gauge stop 30, the applicator roll is caused to rotate through 180° and hence adhesive may be applied to two insoles for each complete rotation of the applicator roll 26. By the simple expedient of adjusting the gauge stop 30 relative to the top of the applicator roll, the length of the insole to which adhesive will be applied by backing of the insole away from the gauge stop can be easily increased or decreased, that is, the distance between the line of tangency of the insole with the top of the applicator roll and the gauge stop. The applicator roll has on its surface two cement-receiving surfaces 26a, 26b situated at diametrically disposed positions thereon, the leading ends of which with respect to the direction of rotation are located at opposite ends of a given diameter $d-d$, as shown in FIG. 3, and each of which extends peripherally thereof in a direction opposite to the direction of rotation. There is indexing means provided in conjunction with the drive for the applicator roll operable to stop the applicator roll following each 180° of rotation with the leading end of one of the adhesive-receiving surfaces at the top. Hence it becomes a simple expedient to control the length of the peripheral surface of the applicator roll which will be brought into engagement with the insole as the latter is backed away from the gauge stop by initially rotating the applicator roll to displace the leading end of the applicator surface relative to the gauge stop in a direction corresponding to that of the rotation of the applicator roll to decrease the surface available for applying adhesive to the insole or in a direction opposite to the direction of rotation of the applicator roll to increase the surface available for applying adhesive to the insole. Since the applicator roll rotates in a counter-clockwise direction, the insole is moved away from or backed away from the gauge stop and during such movement adhesive is progressively applied to the insole from the line of its initial tangential contact with the applicator roll when placed in the machine against the gauge stop to the tip end of the insole. It is within the scope of the invention to employ a single cement-receiving surface or to employ more than two cement-receiving surfaces.

FIG. 6 is an elevation as seen from one side of the machine, to wit, the right side in relation to the front of the machine where the operator would be standing for the purpose of placing the insole between the rolls 26 and 28, the applicator roll 26 being mounted on a horizontally disposed shaft 34 journaled at its opposite ends in bearing plates 36-36 secured to the sidewalls 38-38 of a receptacle 40 adapted to hold a body of molten adhesive. The receptacle 40 is supported by legs 42 from the horizontal shelf 22 and is open at the top.

The applicator roll 26 is supported in the receptacle with its lower part close to but spaced from the bottom and its upper part rising above the open top so that its rotating surface picks up adhesive from the receptacle and carries it upwardly above the open top thereof to a level substantially tangent to the upper surface of a rigid plate 40a fixed transversely of the receptacle to the upper edges of the sidewalls by screwbolts 40b. Suitable doctors of conventional kind may be employed to maintain a uniform layer of adhesive of predetermined thickness on the surface of the applicator roll.

The adhesive is rendered molten and maintained molten by a plurality of heating elements 46 removably fixed in the bottom of the receptacle and the applicator roll is maintained at a temperature sufficiently high to keep the adhesive on its surface molten as it rises from the receptacle by a heating ele-

ment 48 mounted in an axial passage 50 provided in the shaft 34 to which current is supplied by means of a pair of rings 52-52 fixed to one end of the shaft for rotation therewith and brushes 54-54 supported on the wall of the receptacle in engagement with the rings, the brushes in turn being adapted to be connected to a suitable source of electric power.

The shaft 34 has fixed to its opposite end a sprocket 56 by means of which it is rotated each time rotation is initiated through 180° as will be described hereinafter.

The holddown roll 28, as related above, is mounted above the applicator roll for movement from a retracted position elevated therefrom to a position in engagement with an insole resting on the applicator roll. To this end the holddown roll 28 is secured to a shaft 58 journaled at the forward ends of a pair of transversely spaced rocker arms 60-60. The rear ends of the rocker arms 60-60 are mounted on a horizontally disposed shaft 62, the opposite ends of which are rotatably journaled in the upper ends of bearing blocks 64-64. The lower ends of the bearing blocks are secured to the sidewalls of the receptacle 40. The rear end of each rocker arm 60 is bifurcated as at 66 to enable clamping the rocker arm to the shaft 62 by means of a clamp bolt (not shown) arranged to draw the bifurcated portions of the arm into clamping engagement therewith. The shaft 62 extends through the bearing block 64 at the left side of the machine, as shown in FIG. 7, and has mounted on it a sprocket 66, the sprocket teeth of which lie in the same plane as the sprocket teeth of the sprocket 56. Outwardly of the sprocket 66 there is an arm 68, FIG. 6, which is bifurcated at 70 and clamped to the shaft 62 by means of a clamp bolt 72. The arm 68 is adapted by rotation relative to the axis of the shaft 62 to rotate the shaft 62 and hence to rotate the rocker arms 60-60 in a counterclockwise direction as shown in FIG. 6 to move the holddown roll 28 downwardly into engagement with an insole resting on the applicator roll.

Rotation of the arm 68 is effected by means of a pneumatically operated piston-and-cylinder assembly 74 (FIG. 6). The piston-and-cylinder assembly comprises a cylinder 76, one end of which is pivotally supported by a pin 78 mounted between a pair of spaced upstanding blocks 80-80 fixed to the shelf 22. A piston rod 82 extends from the opposite end of the cylinder 76 and is provided with a clevis 84 for receiving the lower end of the arm 68 and is connected thereto by a pin 85. Extension of the rod 82 from the cylinder will rotate the rocker arms 60-60 in an anticlockwise direction. Withdrawal of the piston rod 82 into the cylinder 76 will rotate the rocker arms in a clockwise direction to elevate the holddown roll 28 from the applicator roll. A cam-actuated valve V3 controls the supply of pressure to the cylinder 76.

As previously mentioned, a gauge stop 30 is provided for initially positioning the insole for application of adhesive thereto. As illustrated in FIG. 6, the gauge stop comprises a vertically disposed toe 86 at the lower end of a vertically rising, rearwardly offset leg 88. The leg 88 is pivotally connected to the upper end of a post 90 by means of a piano hinge 92, one leaf 94 of which is secured by screws 98 to the upper end of the post 90 and the other leaf 96 of which is secured to the upper end of the leg 88 by screwbolts 99. The lower end of the post 90 is provided with a foot 110 by means of which it is adjustably secured to the plate 40a for movement forwardly and rearwardly relative to the applicator roll, as will appear hereinafter. A valve block V1 is secured by means of a bracket 100 to the rear side of the post 90 over an aperture 102 of such a size as to expose a valve pin p held distended within the aperture by a spring s . A screw 104 is threaded through the leg 88 in alignment with the aperture in the post 90 and is adjustable therein to a position normally having contact with the spring-backed actuating pin p of the valve when the machine is idle. The spring s holds the leg displaced forwardly at an angle to the post with the toe 86 substantially perpendicular against a limit screw 93 mounted through a hole in the leg and threaded into the post. A locknut 106 is provided for fixing the screw 104 in a predetermined position. The toe 86 is notched at 86a (FIG. 6a) to ride over a ramp 90a fixed to the top of the

plate 40a and has above its lower end a forwardly extending nose 86b. As thus constructed when an end of an insole is pressed against the toe 86 at the lower end of the leg 88, the leg is displaced rearwardly so as to cause the screw 104 to press the actuating pin p inwardly in opposition to the spring s and hence to activate the valve V¹ and to initiate a cycle of operation of the machine as will appear hereinafter. The ramp pushes the end of the insole up into engagement with the toe and the nose prevents it from sliding upwardly too far.

The gauge stop 30, supporting leg 88, post 90 and valve block V¹ are movable as a unit forwardly and rearwardly relative to the applicator roll and to this end the foot 110 at the lower end of the post is secured by a bolt 108 in a slot 112 in the plate 40a.

In conjunction with the gauge stop 30 guide means is provided for centering the leading end of the insole both with respect to the applicator roll and to the gauge stop, the guide means comprising a pair of transversely spaced rollers 200-200 (FIG. 8) mounted to turn on vertically disposed pins 202-202 fixed to the forward ends of transversely spaced arms 204-204. The rear ends of the arms are pivotally mounted on vertically disposed pins 206-206 fixed to laterally extending arms 208-208 which in turn are secured to the post 90. The arms 204-204 have laterally extending shoulders 210-210 recessed to receive springs 212-212 which bias the arms toward each other to hold them engaged with the end of the insole, and to permit them to yield laterally to receive insoles of different transverse width. The arms and the guide rolls supported thereby move forwardly and rearwardly with the gauge stop. The arms 208 are also adjustably secured by means of bolts 209 for adjustment to and from each other transversely of the gauge stop.

The driving means on the lower shelf 24 includes a main drive shaft 114 (FIG. 9) disposed transversely of the machine and journaled for rotation about a horizontal axis in bearing blocks 116-116 fastened to the shelf by screwbolts 118. The right-hand end of the drive shaft 114 extends through its bearing block and has fixed to it a collar 120. The left-hand end of the drive shaft 114 extends through its bearing block and has fixed to it a collar 122, a cam-carrying plate 124, a sprocket 126 and indexing means 128. The cam plate 124 is adjustably secured to the shaft 114 by a split clamp 125 and bolt 127. The sprocket 126 is located so that its teeth are in the plane of the teeth of the sprockets 56 and 66 and a chain 130 is entrained about the sprockets 126, 66 and 56 so that rotation of the drive shaft 114 by rotating the sprocket 126 will in turn effect rotation of the sprocket 66 and the sprocket 56. The sprocket 56 is fixed to the shaft 34. Hence rotation of the drive shaft 114 in a clockwise direction as seen in FIG. 9a effects rotation of the applicator roll in a clockwise direction. The sprocket 66 is free on the shaft 62 and has secured to its hub a gear 132 which meshes with a gear 134 fast to the shaft 58 so that clockwise rotation of the sprocket 66 rotates the gear 132 clockwise and the meshing gear 134 and in turn the holdown roll which is fixed to the shaft 58 in a counterclockwise direction. The rear ends of the rocker arms 60 are, as previously related, fixed to the shaft 62 and when the arms 60-60 are raised or lowered the gear 134 merely rolls around the gear 132.

The drive shaft 114 is rotated through 180°, once rotation is initiated and is automatically brought to a stop at the end of said 180° of rotation and will remain so until the next operation is initiated by placing an insole in tangential engagement with the top surface of the applicator roll and with its forward end pressed against the gauge stop 30. Rotation of the drive shaft is effected by means of a pneumatically operated piston-and-cylinder assembly 140 (FIG. 9) comprising a cylinder 142 mounted in a horizontal position on the shelf 24, with one end pivotally secured thereto on a vertically disposed pin 144. A piston rod 146 protrudes from the opposite end of the cylinder and has on it a clevis 148 for receiving an end of a bracket plate 150 to which it is pivotally connected by a pin 152. The bracket plate is attached by means of bolts 154 to the upper

side of a rack bar 156 slidably mounted in a longitudinally disposed channel 158 in the shelf. A retainer plate 160 is bolted to the shelf over the channel at one end to hold the rack bar at that end in place and at the other end is held in the channel by meshing engagement of a gear wheel 162 with its upper toothed side, the gear wheel being rotatably mounted on a stub shaft 164 overlying the rack. The stub shaft is fixed in this position in a bearing block 163, the latter in turn being fastened to the shelf. A gear wheel 165 internally of which is a freewheeling, one-direction clutch 166, is mounted on the drive shaft 114 in mesh with the rack bar 156. The clutch 166 provides for imparting rotation of the gear wheel 165 to the drive shaft in one direction of rotation and permits the drive shaft to remain stationary while the gear wheel is rotated in the opposite direction, so that forward movement of the rack bar imparts rotation to the drive shaft 114 and rearward movement or retractive movement of the rack bar is permitted without reversing the direction of rotation of the drive shaft.

Due to the fact that the applicator roll and the holdown roll are quite heavy and when once set in motion would tend to continue to rotate, it is necessary to provide means for bringing them to rest without overtravel and this is accomplished by means of an indexing pin 168 (FIG. 9) provided with a conical end 170 for engagement with one of two diametrically disposed conical recesses 172-172 in the peripheral surface of a disc 174 fastened by means of a pin 176 to the drive shaft 114. The index pin 168 is supported in radial alignment with the disc 174 by means of a block 178 with the end opposite the conical end pivotally connected within a clevis 180 by means of a pin 182. The clevis 180 is secured to the protruding end of a piston rod 184 of a pneumatic piston-and-cylinder assembly 186 comprising a cylinder 188 and a rod 184. The opposite end of the cylinder 188 is pivotally connected by a pin 190 to the shelf 24. When the machine is idle the indexing pin 168 is held engaged with the disc 174 so as to hold the drive shaft 114 in a fixed predetermined position. At the instant of initiating operation of the machine, the piston rod 184 is retracted so as in turn to retract the indexing pin 168 to free the drive shaft and thus permit it to rotate. As soon as the rotation is initiated and the conical recess 172 has traveled beyond the conical end of the index pin, the piston rod is extended to hold the index pin against the surface of the disc so that when the next recess reaches the index pin the latter will enter it and stop the drive shaft 114.

As pointed out above, the machine is automatically started by the simple expedient of placing an insole in tangential engagement with the top surface of the adhesive roll with its tip end, whether the toe or heel end, pressed against the gauge stop. Displacement of the gauge stop against the valve V¹ activates the valve V¹ and actuation of the valve V¹, as shown in FIG. 12, supplies pressure from a pressure line L by way of a conductor C¹ to a valve block V² thereby shifting the valve therein so that pressure is supplied from the pressure L through a conductor C²⁰ to the valve V² and through a conductor C²¹, the upper end of the cylinder 188 to thereby retract the piston rod 184 and hence the index pin 168. Pressure supplied to the valve V² is also transmitted therefrom through a conductor C³ to the lower end of the cylinder 142 to extend the piston rod 146 therein and hence to effect rotation of the drive shaft 114. A conductor C⁴ connected to the conductor C¹ between the valves V¹ and V² shifts the valve in the valve block V³ so that line pressure is supplied through conductor C³⁰ to the valve V³ and from thence through a conductor C³¹ to the lower end of the cylinder 76 to extend the piston rod 82 therein and hence to lower the holdown roll into engagement with the insole resting on the applicator roll. When the rack bar reaches the end of its forward or driving stroke, it reverses the position of a valve V⁴ which is mounted on the shelf in a position to be actuated by engagement of the forward end of the rack bar therewith. Reversing the position of the valve V⁴ reverses the position of valve V² so that now fluid pressure is delivered through a conductor C⁸ to the upper end of the cylinder 142 to retract the piston rod therein and hence

to return the rack bar to its initial position. At the same time the half rotation of the drive shaft moves one of the cams 124a, 124b into engagement with the cam roller 124c mounted on a stem extending from the valve V³ and by such engagement reverses its position thereby supplying pressure through conductor C⁶ to the upper end of the cylinder 76 to raise the holddown roll. Pressure supplied to the conductor C⁶ is simultaneously transmitted through a conductor C⁷ connected to the conductor C⁶ to a shuttle valve VS to shift it from right to left and thus to supply pressure through a conductor C⁹ to the lower end of the cylinder 188 to extend the piston rod therein so as to press the index pin against the disc. When the index pin engages the recess in the disc the machine comes to a stop and remains idle until restarted by actuation of the valve V¹ by presentation of another insole to the machine for application of adhesive thereto.

The indexing means 128 comprises a disc 180 containing an opening 181 by means of which it is rotatably mounted on the drive shaft 114 to which there is fastened by means of a rivet 182, or its equivalent, a clamp block 184 provided with a clamp screw 186 by means of which it is clamped to the drive shaft 114. The disc 180 contains peripherally disposed arcuate slots 188a and 188b and behind the disc 180 there is a graduated disc 190 to which there are fixed diametrically disposed threaded studs 192 at radial distances such as to extend through the slots 188a and 188b and on which there are adapted to be threaded clamp nuts 193. The graduated disc 190 is secured by means of a rivet 195, or its equivalent, to the hub of the sprocket 126. By loosening the clamp nuts on the threaded studs extending through the disc 180, the disc 190 may be rotated relative to the disc 180 to in turn rotate the sprocket 126 relative to the drive shaft 114 to establish a predetermined initial position of the applicator roll at the beginning of the operation. To cause the entire length of the adhesive-bearing surface of the applicator roll to be effective, the adjustment will be made to place the index mark "1" on the disc 190 opposite the arrow on the disc 180. If only half of the applicator surface is to be employed, the disc 190 is rotated relative to the disc 180 to bring the index mark "1" opposite the arrow. The effect of this relative rotation is to rotate the applicator roll in an anticlockwise direction to a position such that the midpoint of the applicator surface is at the top and so that when the insole is placed against the applicator roll it will have contact with the adhesive-applying surface at its midlength and hence rotation of the applicator roll will apply only half of the applicator surface to the insole. To provide for initially adjusting the indexing means for applicator rolls of different size, the clamp 184 may be loosened and rotated on the drive shaft 114.

As thus constructed, when the adhesive has been properly melted within the receptacle the operator has only to place an insole in engagement with the upper surface of the applicator roll and push its leading end against the gauge stop whereupon the machine will automatically progressively back the insole out of the machine while simultaneously applying adhesive to that portion of the surface of the insole between its initial line of tangential contact with the applicator roll and the end of the insole engaged with the gauge stop. Having once engaged the insole between the rolls the operator releases it and allows it to be discharged onto the sloping apron at the front of the machine and to be deposited thereby into a receptacle placed at the base of the machine.

I claim:

1. Apparatus for applying adhesive to a predetermined area of an insole at one end comprising a rotatable applicator roll, an adjustable gauge stop supported adjacent the applicator roll at the upgoing side, said gauge stop being located in a position such that a sole blank placed in tangential engagement with the surface of the applicator roll at the top may be thrust into end-abutting engagement with the gauge stop, means for effecting rotation of the applicator roll, and means operable by engagement of the end of the insole blank with the gauge stop operable to initiate rotation of the applicator

roll to move the insole blank away from the gauge stop and simultaneously to apply adhesive to that portion of the insole blank between the initial line of tangency of the insole blank with the applicator roll and the end engaged with the gauge stop.

2. An apparatus for applying adhesive to a predetermined area of an insole at one end comprising a rotatable applicator roll, an adjustable gauge stop supported adjacent the applicator roll at the upgoing side, said gauge stop including an abutment intersecting a plane tangent to the top of the applicator roll at a distance from the line of tangency of said plane with the top of the applicator roll corresponding to the distance along the end of the insole from the tip, to which adhesive is to be applied, means for effecting rotation of the applicator roll, and means operable by engagement of the end of the insole blank with the gauge stop operable to initiate rotation of the applicator roll to move the insole blank away from the gauge stop and simultaneously to apply adhesive to that portion of the insole blank between the initial line of tangency of the insole blank with the applicator roll and the end of the insole abutting the gauge stop.

3. An apparatus for applying adhesive to a predetermined area of an insole at one end comprising an applicator roll, an adjustable gauge stop supported adjacent the applicator roll in a position such that a plane tangent to the surface of the applicator roll will intersect said gauge stop and the distance between the line of tangency of the plane with the applicator roll and the line of intersection of the plane with the gauge stop corresponds to the distance along the end of the insole from the tip, to which adhesive is to be applied, means for effecting rotation of the applicator roll in a direction such that the increment of its surface in said plane of tangency at any given time travels away from the gauge stop, and means operable by placing the insole with the end to which the adhesive is to be applied in tangential engagement with the applicator roll and with its tip at that end in engagement with the gauge stop to initiate rotation of said applicator roll.

4. An apparatus for applying adhesive to a predetermined area of an insole at one end comprising an applicator roll, a gauge stop supported adjacent the applicator roll in a position such that a plane tangent to the surface of the applicator roll will intersect said gauge stop at an angle normal thereto and at a distance between the line of tangency of said plane with the applicator roll and the line of intersection of the plane with the gauge stop corresponds to the distance along the insole from the tip to which the adhesive is to be applied, means for effecting rotation of the applicator roll in a direction such that any increment of its surface in the plane of tangency travels away from the gauge stop, and means operable by placing an insole in tangential engagement with the applicator roll and with its tip in engagement with the gauge stop to initiate rotation of the applicator roll.

5. Apparatus according to claim 4, comprising means supporting the gauge stop for adjustment relative to the applicator roll to increase or decrease the distance between the applicator roll and the gauge stop in said plane of tangency.

6. Apparatus according to claim 4, comprising a holdown roll rotatable about an axis parallel to the axis of rotation of the applicator roll, said holdown roll being cooperable with the applicator roll to hold the insole engaged therewith during rotation of the applicator roll.

7. An apparatus for applying adhesive to a predetermined area of an insole at one end comprising an applicator roll, a gauge stop supported adjacent the applicator roll in a position such that a plane tangent to the surface of the applicator roll will intersect said gauge stop at an angle normal thereto, and that the distance between the line of tangency of said plane with the applicator roll and the line of intersection of the plane with the gauge stop corresponds to the distance along the insole from the tip to which the adhesive is to be applied, a holdown roll supported for rotation about an axis parallel to the axis of rotation of the applicator roll, means normally holding said holdown roll in a retracted position spaced from the sur-

face of the applicator roll for movement into engagement with an insole resting on the applicator roll at the line of tangency of the insole with the applicator roll, means for effecting rotation of the applicator roll in a direction such that the insole is moved away from said gauge stop, and means operable to move said holdown roll from said retracted position into engagement with said insole blank resting on the applicator roll substantially simultaneously with initiation of the rotation of the applicator roll.

8. Apparatus according to claim 7, comprising means for retracting said holdown roll from the applicator roll simultaneously with the arrival of the tip of the insole at said line of tangency as it is backed away from the gauge stop.

9. An apparatus for applying adhesive to a predetermined area of an insole at one end comprising an applicator roll, a gauge stop supported adjacent the applicator roll in a position such that a plane tangent to the surface of the applicator roll will intersect said gauge stop at an angle substantially normal thereto and that the distance between the line of tangency of said plane with the applicator roll and the line of intersection of the plane with the gauge stop corresponds to the span of adhesive to be applied to the insole, a holdown roll cooperable with the applicator roll to hold the insole engaged therewith, means normally holding said holdown roll in a retracted position spaced from the applicator roll means for effecting rotation of the applicator roll in a direction to move the insole away from the gauge stop, and means for simultaneously effecting rotation of said holdown roll and moving it from said retracted position into engagement with the insole resting on the applicator roll.

10. Apparatus according to claim 1, wherein the applicator roll has on its surface diametrically disposed adhesive-receiving surfaces, each of which is sufficiently long peripherally of the surface to apply adhesive to the insole throughout the maximum distance along the sides required for end lasting, and means for effecting rotation of the applicator roll through 180° each time rotation is initiated.

11. Apparatus according to claim 1, wherein the applicator roll has on its surface at diametrically opposed ends of a given diameter two adhesive-receiving surfaces of predetermined length, the leading end of one surface being located at one end of said diameter and extending in a direction opposite to the direction of rotation toward the other, and the leading end of the other being located at the other end of said diameter and extending in a direction opposite to the direction of rotation toward the one, means for positioning the applicator roll with the leading end of one of said surfaces at said line of tangency, and means for effecting rotation of the applicator roll through 180° and terminating its rotation with the leading end of the other of said surfaces at said line of tangency.

12. Apparatus according to claim 1, comprising centering means flanking the gauge stop for receiving the end of the insole and centering it with respect to said gauge stop and the applicator roll.

13. Apparatus according to claim 1, comprising centering means flanking the gauge stop, said centering means comprising transversely spaced rollers between which the end of an insole is adapted to be thrust for engagement with the gauge stop to center the end of the insole with respect to said gauge stop.

14. Apparatus according to claim 1, comprising centering means flanking the gauge stop, said centering means comprising transversely spaced rollers between which the end of the insole is adapted to be thrust into engagement with the gauge stop, and laterally yieldable arms supporting said rollers for receiving insoles of different transverse width.

15. Apparatus according to claim 1, comprising centering means flanking the gauge stop for receiving the end of the insole and centering it with respect to said gauge stop, and means mounting the centering means and the gauge stop for movement in unison toward and away from the applicator roll.

16. Apparatus according to claim 1, wherein the gauge stop comprises a bar pivotally supported at its upper end in a

predetermined upright position with the end constituting the gauge stop substantially at right angles to the plane of tangency, said bar being movable by engagement of the end of the insole therewith away from said predetermined position, and means operable by movement of the bar away from said predetermined position to initiate rotation of the applicator roll.

17. Apparatus according to claim 16, comprising a part situated above the lower extremity of the gauge stop, said part extending therefrom in the direction of the applicator roll and constituting a holdown for the end of the insole when the latter is thrust against the gauge stop.

18. Apparatus according to claim 17, comprising a ramp having an inclined surface, said ramp being situated at the lower end of the gauge stop subjacent said part, and said gauge stop having at its lower extremity a bifurcated portion for receiving said ramp.

19. Apparatus according to claim 1, wherein the applicator roll has on it an adhesive-receiving surface having leading and trailing ends, and means for initially adjusting the position of the applicator roll with respect to said line of tangency to place the leading end of said surface beyond the line of tangency in the direction of rotation.

20. Apparatus according to claim 1, wherein the applicator roll has on it two adhesive-receiving surfaces arranged so that the leading end of one surface is 180° from the leading end of the other.

21. Apparatus according to claim 19, wherein said means for initially adjusting the position of the applicator roll with respect to the line of tangency includes means for stopping the rotation of the applicator roll when the adhesive-receiving surface has rotated through a distance corresponding to the difference between its entire peripheral length and the distance the leading end of the adhesive-receiving surface was initially offset with respect to said line of tangency.

22. Apparatus according to claim 19, wherein the means for initially adjusting the position of the applicator roll comprises as a component a sprocket adjustably fixed to the drive shaft adapted to be rotated with respect thereto and cam means for terminating rotation of the drive shaft.

23. Apparatus according to claim 1, wherein the applicator roll has on it an adhesive-receiving surface which projected onto a plane surface is substantially U-shaped, comprising an end portion extending across the applicator roll from end to end and peripherally of the roll a predetermined arcuate distance, and side portions adjacent the ends of the roll which extend from the end portion peripherally of the roll in spaced parallel relation, the distance between said side portions being less than the transverse width of the insole to which adhesive is to be applied, means for initially displacing the leading end of the adhesive-applying surface in the direction of rotation relative to said line of tangency, and means for effecting rotation of the applicator roll each time its rotation is initiated through a distance sufficient to bring the leading end of one of said adhesive-receiving surfaces back to said initial position with respect to said line of tangency.

24. Apparatus according to claim 1, wherein the applicator roll has on it symmetrically disposed adhesive-receiving surfaces, each of which if projected onto a flat plane is substantially U-shaped in configuration, comprising an end portion extending across the roll from end to end and peripherally thereof a predetermined distance which is at least as great as the widest band of adhesive to be applied across the end of the insole, and portions adjacent the ends of the roll extending peripherally of the end portion in spaced parallel relation, the proximity of the spaced portions being such as to apply a band of adhesive of predetermined width along each side of the insole, means for effecting rotation of the applicator roll through 180° each time rotation is initiated to cause one of the adhesive-receiving surfaces to have rolling contact with the insole placed in engagement therewith and following rotation to bring the other adhesive-receiving surface into position for engagement with an insole, and means for initially displacing the

applicator roll in the direction of rotation to enable controlling the width of the band of adhesive applied across the end of the insole and the lengths of the bands of adhesive applied along the sides of the insole.

25. Apparatus according to claim 1, wherein the applicator roll has a plurality of peripherally disposed, uniformly spaced adhesive-receiving surfaces, means for effecting rotation of the applicator roll to cause one of the adhesive-receiving surfaces to move through a distance such as to progressively present its entire surface from beginning to end to said predetermined line of tangency and to bring the leading end of the next adhesive-receiving surface to said line of tangency each time rotation of the roll is initiated, and means for initially adjusting the position of the applicator roll with respect to said line of tangency to displace the leading ends of said adhesive-receiving surfaces away from said line of tangency in the direction of rotation.

26. Apparatus according to claim 1, wherein the applicator roll has diametrically disposed adhesive-receiving surfaces, one on each half-surface of the roll, and wherein the means for effecting rotation of the roll comprises a drive shaft, means operably connecting said drive shaft to the applicator roll for effecting its rotation, means for effecting rotation of the drive shaft each time its rotation is initiated through a half revolution, and adjustable means embodied in the means connecting the drive shaft to the applicator roll to initially displace the applicator roll with respect to the drive shaft.

27. Apparatus according to claim 1, wherein a shaft supports the applicator roll for rotation and said means for effecting rotation of the applicator roll comprises a drive shaft, sprockets on said shaft on which the applicator roll is mounted and said drive shaft, a chain entrained about said sprockets, means for effecting rotation of the drive shaft, said means being operable each time rotation of the drive shaft is initiated to rotate said drive shaft and hence the applicator roll through a predetermined angular distance, and means adjustably connecting one of the sprockets to its shaft, said last-mentioned means being adjustable on said shaft to enable displacing the applicator roll forwardly or rearwardly relative to said drive shaft.

28. Apparatus according to claim 27, comprising cam means on said drive shaft operable to effect retraction of the holddown roll at the end of said predetermined angular distance.

29. Apparatus according to claim 27, wherein the sprocket on the drive shaft is adjustably connected thereto by said adjustable means and comprises a disc fixed to said drive shaft, said disc containing peripherally disposed arcuate slots, studs fixed to the sprocket in positions to extend through said slots

in the disc, said sprocket being loose on the shaft, and means for locking the studs in said slots at a predetermined position of adjustment of the sprocket relative to the disc.

30. Apparatus according to claim 1, wherein a shaft supports the applicator roll for rotation and the means for effecting rotation of the applicator roll comprises a drive shaft, a holddown roll, a pair of arms between the forward ends of which the holddown roll is rotatably mounted, a rocker shaft upon which the rear ends of the arms are fixed, said shaft being supported in spaced parallel relation to the axis of rotation of the applicator roll for oscillation, for movement in one direction to lift the holddown roll away from the applicator roll and in another direction to move the holddown roll into engagement with an insole resting on the applicator roll, an arm fixed to said latter shaft for effecting its oscillation, a sprocket loosely mounted on said oscillating shaft adapted to be rotated in consonance with the rotation of the applicator roll by a chain entrained about it and about sprockets on the drive shaft and the shaft of the applicator roll, a gear fixed to said sprocket on said oscillating shaft and a gear on the shaft of the holddown roll in mesh therewith, said latter gear being rotatable around the axis of the gear on the oscillating shaft as the holddown roll is moved into and out of operative position.

31. Apparatus according to claim 30, wherein a first motor is operably connected said drive shaft to effect its rotation a predetermined distance, a second motor is operably connected to the rocker shaft to effect its oscillation to bring the holddown roll into engagement with the insole when the operation is initiated and to lift it away from the insole when rotation of the drive shaft is terminated, an index stop cooperable with the drive shaft to limit its terminal movement, and a motor operably connected thereto operable to disable the index stop simultaneously with initiation of operation and to enable it prior to termination of the rotation of the drive shaft.

32. Apparatus according to claim 28, comprising means for adjustably securing the cam means to the drive shaft.

33. Apparatus according to claim 31, wherein said motors comprise pneumatically operable cylinder and piston assemblies, and wherein there are a plurality of valves comprising a first valve shiftable by said gauge stop to supply pressure through second and third valves to said motors to retract the index stop to effect rotation of the drive shaft and lower the holddown roll into operative position, and wherein there is a fourth valve operable to reverse the position of the second valve when the drive shaft is rotated through a predetermined distance to return one motor to its initial position and by reversing the position of the third valve restoring the first and second motors to their initial position.
